UNITED STATES PATENT OFFICE

2,538,324

BABY WALKER

Arthur J. Petrie, Oklahoma City, Okla.

Application March 22, 1949, Serial No. 82,715

1 Claim. (Cl. 155—24)

1

This invention relates to a baby walker, the primary object of the invention being to provide a baby walker which is so supported with respect to the casters that it will not tilt over, when the infant strapped in the seat portion thereof leans backwardly or forwardly in the walker.

Another important object of the invention is to provide a lower guard ring, which is attached to the supporting legs of the walker in such a way that it will extend downwardly an appreciable distance in close proximity to the floor surface on which the walker is positioned.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawing:

Figure 1 is a perspective view of a baby walker, constructed in accordance with the invention.

Fig. 2 is a fragmental enlarged view illustrating the manner of securing the seat suspension straps to the walker.

Fig. 3 is a fragmental perspective view illustrating one method of securing the casters to the walker.

Fig. 4 is a perspective view of a modified form of caster supporting means.

Fig. 5 is a fragmental perspective view illustrating a further modified form of guard ring.

Referring to the drawing in detail, the walker comprises the upper ring member 5 and the lower ring member 6, the ring member 6 being of a diameter appreciably greater than the diameter of the upper ring member 5, which is only slightly larger than the body of the infant using the walker, so that the ring will act as a means to hold the infant within the walker.

As shown, the rings 5 and 6 are connected by means of the legs 7 that are preferably welded at their upper ends, to the ring 5, while the lower ends thereof are welded to the inner surface of the ring 6. As shown, the ring 6 is formed with upwardly curved portions 8, the legs 7 being secured to the lower ring at the upwardly curved portions 8, as clearly shown by Fig. 1 of the drawing. Due to the curved portions 8, it will be obvious that the main portions of the lower ring 6 extend downwardly to points adjacent to the upper edges of the casters 9 which are fitted in the ends of the legs 7 that are constructed preferably of tubular material to receive the shanks 55

2

of the casters 9. Because of the curved portions 8, the ring extends outwardly appreciable distances between the legs 7 presenting a guard ring to contact with the floor surface, should the infant using the walker, attempt to lean forwardly or rearwardly to tilt the walker. It is obvious that the edge of the guard ring will contact with the surface on which the walker is positioned, and prevent the overturning of the walker.

10 Portions of the legs 7, at 10, are pressed inwardly providing an enlargement interiorly of the tubular legs, which enlargements cooperate with an annular groove formed at the upper end of the shank 11 of a caster, to hold the casters in place.

15 In the form of the invention as shown by Fig. 4 of the drawing, the tubular legs 12 are supported appreciable distances within the lower ring 13 and are connected with the ring 13, by means of the curved arms 14 that are welded to the ring 13 and also welded to the legs 12. With this construction, it will be seen that the casters 15 are supported an appreciable distance within the confines of the lower ring 13 with the result that the ring 13 projects beyond the casters to act as a guard rail, contacting with the surface on which the walker is used, to prevent the walker from toppling over when the infant leans forwardly or rearwardly.

20 In the form of the invention as shown by Fig. 5, the lower guard ring, which is indicated by the reference character 16 is formed with offsets 17 disposed downwardly so that they lie in close proximity to the surface on which the walker is being used, to contact with the ground surface and guard against the walker tilting over when the infant moves rearwardly or forwardly.

25 In this form of the invention, the tubular leg members 18 are secured to the ring, at points between the offsets 17, the ends of the leg members being open, to receive casters, which are not shown in the present drawing, but which are positioned with their shanks extending into the open lower ends of the leg members 18.

30 As shown by Fig. 2 of the drawing, the upper ends of the leg members are formed with openings 19 and the buckles 20 are secured in these openings, with their lower ends disposed downwardly, the lower ends providing means for attaching the seat supporting straps 21 to the walker. The seat is indicated by the reference character 22, the straps 21 being secured to the seat in any desirable manner, the straps 21 permitting of adjustment of the seat with respect to

the upper ring 5, to properly support the seat for the comfort of the infant using the walker.

Secured on the lower ring member 6 is a rubber protecting band 23 which acts as a bumper and prevents the walker from being forced into engagement with articles of furniture or the like to scar the same.

Having thus described the invention, what is claimed is:

A baby walker comprising upper and lower ring members, the lower ring member being of a diameter appreciably greater than the upper ring member, tubular legs connecting the upper and lower ring members holding the ring members in vertical spaced relation with respect to each other, said legs being connected to the lower ring member at the inner edge of the lower ring member, casters having shanks extending into the tubular legs adjacent to the lower ring member

within the confines of said lower ring member, portions of the lower ring member between the casters being extended downwardly in proximity with the surface on which the baby walker rests providing a guard, and a seat suspended from the upper portion of the walker.

ARTHUR J. PETRIE.
